SUCTION CLEANER

Donald G. Smellie, Canton, Ohio, assignor to
 The Hoover Company, North Canton, Ohio, a
 corporation of Ohio

Application July 10, 1939, Serial No. 283,517

4 Claims. (CL 15—183)

The present invention relates to suction cleaners in general and more particularly to a new and novel rotary agitator for a suction cleaner. More specifically the invention comprises a new and improved agitating element adjustment construction in a rotary agitator for a suction cleaner.

It is an object of the present invention to provide a new and improved suction cleaner. It is another object of the invention to provide a new and improved suction cleaner rotary agitator. A further object of the invention is to provide new and improved agitating element adjusting means in a rotary agitator for a suction cleaner. A further object of the invention is to provide means to adjust the brush element radially in a rotary agitator for a suction cleaner which means are so constructed and arranged as to prevent clogging with foreign material, etc. Still another object of the invention is to provide a rotary agitator in which the brush element is radially adjustable by manually operable means which are so related that it is not necessary to reverse the brush end for end. These and other more specific objects will appear upon reading the following specification and claims and upon considering in connection therewith the attached drawing to which they relate.

Referring now to the drawing in which a preferred embodiment of the present invention is illustrated, and in which the same reference character refers to the same parts throughout:

Figure 1 is a front view of a suction cleaner embodying the present invention with the nozzle broken away and shown in section to illustrate the suction cleaner agitator embodying the present invention positioned therein;

Figure 2 is a partial longitudinal section through the agitator;

Figure 3 is a partial side elevation of the rotary agitator constructed in accordance with the present invention with certain parts of the cylindrical casing broken away and the adjustable brush element illustrated in its outer radial position;

Figure 4 is a section through the brush securing means of the agitator upon the line 4—4 of Figure 2; and

Figure 5 is a section upon the line 5—5 of Figure 2.

In the modern suction cleaner rigid beating elements and flexible brush elements are provided which cooperate in beating and brushing the surface covering undergoing cleaning. The brush elements are made of flexible bristles which are subject to wear and after a certain period

of use, it becomes necessary that they be adjusted radially in order that they continue to operate satisfactorily. The present invention is directed to a construction by which the agitating elements subject to wear can be adjusted radially in a simple manner and by a construction which cannot be clogged by the foreign material with which the agitator is always in contact in operation.

Referring again to the drawing, and to Figure 1 in particular, a modern suction cleaner is shown and is seen to comprise a nozzle 1 which is interiorly connected through a passageway 2 to a fan chamber 3 which houses a suction-creating fan 4. The fan 4 is carried by the depending motor shaft 5 which extends downwardly from an unshown motor positioned within the motor casing 6 immediately above the fan chamber. Within the cleaner nozzle 1 is positioned an agitator, indicated generally by the reference character 10, which is rotatably supported by a through supporting shaft 11 and which is seen to comprise a cylindrical body 12 upon the surface of which are helically extending rigid beater bars 13. Body 12 is provided with axially extending brush seats 14 within each of which is adjustably positioned a brush element indicated generally by 15. Agitator 10 is driven from the depending motor shaft 5 by a power-transmitting belt 16 and in the operation of the machine is adapted to contact a surface covering undergoing cleaning below the nozzle. The cleaner is movably supported by wheels 18 and there is provided, as in the usual suction cleaner, a handle 19 by which the operator may exert the propelling force, the incoming current leads being carried by the handle and extending down into the motor casing 6.

The cylindrical hollow body 12 of the agitator 10 has each of its ends closed by an end plate 20 which centrally seats a ball bearing 21 held in place by a thread guard 27 screwed upon the end of the shaft 11. The shaft 11 itself seats the inner race of the ball bearing 21.

The flexible agitating element or brush 15 of the agitator is adjustably positioned within the open bottom seat 14 which is seen to comprise side walls 17 and axially spaced end walls 22. The inner end wall 22, that adjacent the pulley, is seen to be formed with a downwardly facing shoulder 23 and to be spaced under the extension of the body 12 thereabove which in effect forms a second downwardly facing shoulder 24. At the opposite or outer end of each brush seat the end wall 22 is formed with a lower upwardly

facing shoulder 25 and an upper upwardly facing shoulder 26. Carried by the body 12 and extended under the inwardly facing shoulders 23 and 24 is an elongated leaf spring 28 which is adapted to underlie the brush back to force it upwardly into contact with the shoulders as will be explained. In the case of the outer shoulders 25 and 26, the lower shoulder 25 is provided with an internally threaded bore 30 which seats the threaded bolt 31, the headed end of which is adapted to clamp the end of the brush back in place. The side walls 17 of the agitator brush seat 14 are parallel and at their lower ends are provided with inturned shoulders 32 which are adapted to cooperate with the shoulders 25 and 23 in positioning the brush element in its lower radial position.

The removable brush element itself is seen to comprise a rigid metallic back 34, the ends of which are adapted to abut and underlie the shoulders 23 and 24 at the inner end of the brush seat and overlie shoulders 25 and 26 at the outer end thereof. The longitudinally extending sides of the back 34 also contact the seat shoulders 32 in the lower radial position. Extending the length of the back 34 is a shaft 36 upon which are pivotally mounted a series of adjacent brush tuft seats 37 each of which carries a flexible brush tuft 38. The body 34 is made in a V-shape which permits each of the tuft seats 37 a range of pivotal movement about the supporting shaft 36.

The cleaner being in operation and the suction-creating fan 4 rotating, a flow of cleaning air is moved through the cleaner which effects the lifting of a surface covering upwardly and into contact with the agitator 10. The rotation of the agitator by the belt 16 results in the vibrating and brushing of the covering which dislodges the embedded foreign material therein. With the agitator in its new condition the brush elements or tufts extend substantially to the same radial extension as the rigid beating elements 13. After the cleaner has been in use for a prolonged period, however, the ends of the brush tufts 38 of the brush 15 become worn and decrease in length. It then becomes necessary for the operator to adjust the brush manually. In its new brush position, as illustrated in Figure 2, the rigid back 34 was positioned in the brush seat 14 with its inner end seated under the overlying shoulder 23 against which it was held by the action of the flat spring 28 in contact with the end thereof. The opposite end of the back was secured to the outwardly facing shoulder 25 by the headed screw 31 which passed therethrough in a slot 35. To adjust the brush the operator needs only to loosen the screw 31 enough to permit the brush to be moved outwardly a sufficient distance at its outer end that that end can pass out and over the outwardly facing shoulder 26, the slot 35 permitting this axial movement. At such time the opposite end of

the back will be disengaged from the shoulder 23 and will be forced by spring 28 outwardly into contact with the overlying shoulder 26. The operator then tightens the securing bolt 31 and the brush element is again fixed in place.

Among the advantages of the brush adjustment of the present invention is the fact that it is not necessary to remove the brush from the agitator to accomplish the adjustment. The operator need only loosen the screw 31, move the brush element slightly axially, and tighten the screw again. A further advantage of the construction is that there are no openings at the ends of the agitator brush which can become filled with foreign material to prevent the adjustment.

I claim:

1. A rotary agitator for a suction cleaner comprising a body formed with an agitating element seat, a plurality of abutments at the opposite ends of said seat, the abutments at each end of said seat being spaced vertically therein and lengthwise of said seat, an agitating element in said seat adapted at its opposite ends to contact selectively said abutments at various heights therein upon being shifted lengthwise of said seat and for the purpose of varying the height of said element relative to said seat, means at one end of said seat to urge said element in all of its lengthwise positions outwardly against the abutments at that end, and means at the opposite end of said seat to urge said element inwardly in all of its lengthwise positions against the abutments at that end.

2. A rotary agitator for a suction cleaner comprising a body formed with an agitating element seat, an agitating element including a rigid back positioned therein, shiftable lengthwise therein, and radially relative to the axis of rotation of said body, means to abut said element from above at one end thereof in its various lengthwise and radial positions and from below in its various lengthwise and radial positions at the other end thereof, and means at the opposite ends of said element to exert oppositely directed forces thereon to hold it against said abutments.

3. The construction recited by the preceding claim characterized in that the said last-mentioned means comprise a spring carried by said body externally of and at one end of said seat.

4. A rotary agitator for a suction cleaner comprising an elongated cylindrical body formed in the mid-portion with a pulley surface of reduced diameter, an elongated brush seat in said body upon one side of said pulley surface, and an elongated flexible leaf spring carried by said body upon the opposite side of said pulley and extended under said pulley surface into a position below said seat in which it is adapted to contact a brush positioned in said seat and exert an outwardly directed force thereon.

DONALD G. SMELLIE.
